UNITED STATES PATENT OFFICE.

OSMYN MOWERS, OF HOUSTON, TEXAS.

PUMP.

Application filed August 11, 1924, Serial No. 731,512. Renewed September 18, 1925.

To all whom it may concern:

Be it known that I, OSMYN MOWERS, a citizen of the United States, residing at Houston, Harris County, Texas, have invented a certain new and useful Improvement in Pumps, of which the following is a specification.

My invention relates to an improvement in pumps and has particular application to 10 plungers, or "suckers," to be used in reciprocating pumps employed in pumping oil or water from deep wells.

An object of my invention is to provide 15 a plunger for deep well pumps which will be adapted for working in all kinds of tubing without the necessity of the usual working barrel.

Another object is to provide a plunger of 20 this kind wherein the stream of fluid being pumped will pass largely outside of the plunger and between the same and the tubing thereby largely avoiding the difficulty of the clogging of the plunger valve.

Another object is to provide a cup in connection with this type of pump plunger 25 which will be collapsible and so supported as to prevent too great expansion of the cup on the upward stroke. These and other objects and advantages will be brought out 30 with greater clearness in the specification which follows:

Referring to the drawing herewith wherein like numerals of reference are employed throughout both views to designate like 35 parts; Fig. 1 is a longitudinal section through a length of tubing showing my type of plunger employed therein, said plunger being in elevation. Fig. 2 is a central longitudinal section through a pump plunger employing my invention.

This invention is an improvement on the 40 plunger disclosed in my prior application No. 418,899, filed October 23, 1920. This type of plunger may be, and usually is employed in a sort of tandem arrangement, there being a plurality of plungers upon the sucker rod positioned at intervals along the rod. In Fig. 1, I have indicated such an arrangement. In this view the tubing 1 is 45 intended to represent any ordinary type of tubing and it will be noted that no special working barrel is necessary. The plungers designated by the numeral 2 are coupled into an ordinary string of sucker rod 3, such as is commonly employed in pumping.

Each of these plungers is constructed in

accordance with the structure shown in Fig. 2. The central head of this plunger comprises a section of tubular pipe 4 threaded at its upper end for coupling within an ordinary solid sucker rod. The lower end at 5 is also similarly threaded for attachment within a coupling member 6. This length of pipe is of uniform diameter and has intermediate the ends thereof a circumferential flange 7. This flange is formed by shrinking upon the pipe a metal ring of the same material as the pipe. The passage 8 through the head 4 is enlarged at a point about even with the flange 7 to form a valve seat 9 to accommodate a ball valve 10 adapted to seat therein. Within the enlarged upper portion of the passage through the tubing I fix a pin 11, diametrically across the pipe to limit the upward movement of the ball valve. At a point immediately above the valve I form a plurality of radial openings 12 to allow the passage of liquid therethrough.

The coupling 6, to which the lower end of the pipe 4 is connected, is formed into an outwardly flaring cup 13 towards the upper end, but below the cup 13 it is reduced in diameter at 14 and has at the lower end an internally threaded socket 15 for coupling within the sucker rod. At the lower end of the threaded socket into which the threaded end 5 of the head is attached, I form radial openings 16, allowing the passage of fluid inwardly to a chamber 17 connected with the lower end of the said head 4. Within the cup-shaped upper end of the coupling there is formed a shoulder 18 against which the lower end of a flexible cup 19 is adapted to seat.

The cup 19 forms the suction member of my plunger. It may be made up of any flexible wear resisting material such as rubber or various compositions. It is frusto conical in shape, having the lower end 20 formed to fit within the support formed by the coupling 13 and has intermediate the ends thereof, an interior shoulder 21 adapted to contact with the lower face of the ring 7. The internal diameter of the cup is enlarged for that purpose to a point somewhat above the ring and then is flared outwardly at 22 to form a suction member. The outer face of the cup is inclined outwardly toward the upper end and has at a point immediately above the support 13 a shoulder 23.

It will be noted that the cup 19 is formed of such thickness that it will largely support its load of fluid without much assistance. I have provided, however, the support formed by the outer rigid cup 13 extending to a point somewhat above the middle portion of the sucker. The upper end is flared outwardly above the support so that it will contact lightly with the interior face of the tubing. On the downward stroke of the plunger the cup will be allowed to collapse sufficient to allow the fluid being pumped to pass upwardly outside of the cup and the larger part of the fluid thus pumped will move upwardly outside of the cup as the plunger moves downwardly. On the upward stroke the head of fluid in the pump barrel will be supported by the cup and this load will serve to force the cup outwardly against the inner face of the tube with such force to form a tight fit therewith.

When the plunger is used in fluid containing quantities of sand or other sediment, the upper end of the cup tends to become clogged with the sand settling back therein. It is to avoid this clogging of the cup with sand, that a small portion of the fluid is allowed to find a passage upwardly through the plunger. Thus on the downward stroke a small stream of the fluid will flow inwardly through the opening 16 into the passage 8 within the pipe 4 and will raise the valve from its seat and allow this liquid to be forced outwardly through the openings 12 and upwardly through the upper end of the cup, thus carrying the sand in suspension with it to the surface.

In the assembling of this device the flexible cup 19 is seated within the upper end of the coupling 6 and the pipe 4 is inserted downwardly into the cup and screwed within the said coupling. When the parts are thus tightened together the ring 7 will clamp the lower end of the cup between the shoulders 21 and 18, thus holding the cup securely in position. It will be obvious however, that the cup may be quickly removed when necessity arises by simply unscrewing and withdrawing the length of pipe 4.

It has been found in practice that a plunger thus formed will work for comparatively long periods of time without material wear upon the cup. The manner in which this cup may be expanded by the weight of the load of fluid above it, makes a tight fit assured on the working stroke of the plunger. The strength of the cup itself reinforced by the outer cup 13 will prevent undue expansion. The contact of the shoulder 23 of the cup with the cup 13 will limit the backward expansion of the sucker. The device is thus strong in construction and will wear for unusually long

periods of time before replacement is necessary.

Having thus described my invention, the further objects and advantages of which will be clear to one skilled in the art; what I claim is:

1. In a pump, a plunger comprising a tubular head, an annular flange thereon, a cup shaped coupling having a threaded central recess therein to receive the lower end of said head, a cup of flexible material adapted to fit within said coupling and between the same and said flange, and an outer shoulder on said flexible cup fitting over the upper end of said coupling said head being constructed to allow passage of fluid therethrough to clear said cup of sand.

2. In a pump, a plunger comprising a tubular head, a cup shaped coupling to which said head is detachably engaged, an upwardly flaring cup of flexible material, means to clamp said cup in said coupling whereby said flexible cup is supported laterally and a central valve controlled passage through said head whereby said cup may be cleared of sand.

3. In a pump, a pump barrel, a reciprocable sucker rod therein, a tubular head connected in said rod, a cup-shaped coupling connected to said head, an upwardly flaring sucker of flexible material seated in said coupling and supported thereby, said cup adapted to collapse on the downward stroke and expand against said pump barrel on the upward stroke, a shoulder on the outer face of said sucker adapted to rest on said coupling and means on said head to clamp against said sucker in the manner described.

4. In a pump, a pump barrel, a reciprocable sucker rod therein, a cup-shaped sucker of flexible material mounted thereon, a cup-shaped coupling on said rod at the lower end of said sucker to support the same, means on said sucker cooperating with said support to prevent undue expansion thereof, said sucker being adapted to collapse on the downward stroke to allow passage outside thereof for the fluid being pumped.

5. In a pump, a pump barrel, a sucker rod reciprocable therein, a tubular head connected in said rod, a cup-shaped coupling to which said head is engaged, an upwardly flaring sucker of flexible material supported in said coupling and held clamped therein by said head, said coupling having lateral passages therein connecting with said tubular head, and said head having outlet passages within said sucker whereby said sucker may be flushed free of sand.

In testimony whereof I hereunto affix my signature this 2nd day of August, A. D. 1924.

OSMYN MOWERS.
